UNITED STATES PATENT OFFICE.

JAMES HENRY FERGUSON, OF BROOKLYN, NEW YORK.

DESIGN FOR A FAN.

SPECIFICATION forming part of Design No. 16,360, dated November 3, 1885.

Application filed June 25, 1885. Serial No. 169,771. Term of patent 7 years.

To all whom it may concern:

Be it known that I, JAMES HENRY FERGUSON, a citizen of the United States, residing at Brooklyn, in the county of Kings and State 5 of New York, have invented and produced a new and original Design for Fans, of which the following is a specification, reference being had to the accompanying drawing, forming part thereof.

10 The purpose of my invention is to provide a new and peculiar ornamentation for a fan; and the nature of my design is fully illustrated in the view herewith, to which reference is made.

15 *a* in general represents a fan of circular form, and *b* the handle of the same.

The ornamentation on the fan consists of a chart or map delineating a tract or region of country with its general characteristic features 20 of plains, mountains, rivers, and lakes, with intersecting lines to indicate railroads and their branches with stations, and a prominent line provided with spots to indicate stations, said line, in connection with a portion of the 25 contour of the fan, inclosing a space within which is located a landscape view, all combined in a picture to form a peculiar ornamentation.

In the accompanying drawing, *c* represents 30 elevations or mountains; *d*, the lakes, and *e* rivers, with tributary branches *f* of the design. *g* is a prominent line winding across the picture, representing a main railroad with stations *h* and diverging branch lines *i*. The 35 said line *g* extends from one side of the fan in

a horizontal or nearly horizontal line to within a distance from the opposite side of the fan, when it extends in a downward direction, inclosing and forming with a portion of the contour of the fan a space within which is located 40 a suitable landscape view, *l*, inclosed by a circle, the space, circle, and landscape being located at one side of the fan, and divided from the chart or map portion of the picture principally by the said line *g*. *j* are islands, and 45 *k* are lines indicating State divisions.

Prominently placed in the picture consisting of the features heretofore mentioned is a landscape view, *l*, which consists of a brook or stream flowing from the mountains represented in the background, trees and foliage on one side of the brook, and a country-seat bordering on the other.

What I claim as new, and desire to secure by Letters Patent, is—

55 A design for a fan, consisting of a map or chart of a section of country provided with mountains, rivers, intersecting railways, cities, towns, a lake at the upper left-hand portion of the chart, a body of water at the lower 60 right-hand portion, and a prominent line of railway joining the two, and inclosing a space within which is located a landscape view comprising trees, foliage, a stream, and a country-seat, substantially as shown.

JAMES HENRY FERGUSON.
